Patented Aug. 24, 1976

241,169

CHECK PROTECTOR

Joseph A. La Barber, 317 River Oaks Drive,
Bakersfield, Calif. 93309

Filed Feb. 13, 1975, Ser. No. 549,573

Term of patent 14 years

Int. Cl. D19—02

U.S. Cl. D64—10

Fig. 1

Fig. 2

Fig. 3

Fig. 4

Fig. 5

FIG. 1 is a front elevational view of a check protector showing my new design in an unfolded condition;

FIG. 2 is a cross-sectional view taken along line 2—2 of FIG. 1;

FIG. 3 is a front elevational view of the check protector shown in a folded condition;

FIG. 4 is a rear elevational view thereof; and

FIG. 5 is a right end elevational view of FIG. 3.

I claim:

The ornamental design for a check protector, as shown and described.
